EDMUND MORRIS AND ANTHONY VANDERVELD, OF GRAND RAPIDS, MICHIGAN, AS-SIGNORS TO GRAND RAPIDS STORE EQUIPMENT CORPORATION, OF GRAND RAPIDS, MICHIGAN, A CORPORATION OF MICHIGAN

COUNTER-PARTITION SUPPORT

Application filed May 31, 1928. Serial No. 281,797.

This invention relates to counter partition supports and is particularly concerned with a simple, novel means whereby the dividing partitions between parallel cross partitions and vertical border members at the edges of a counter or table top may be securely held with respect to the cross partitions against movement and may be adjusted to different positions when desired.

10 The top of a counter or table used in a store may be divided into a plurality of merchandise receiving and holding compartments.

In accomplishing this purpose vertical side and end border members are attached to the 15 side and end edges of the top, and the space over the top within the border members is divided into bins or compartments which may be of varying dimensions as to length and width. It is designed that vertical cross partitions, of glass preferably, shall extend across the table top between the side border members and a co-pending application for patent filed by Edmund Morris, Serial No. 281,798, dated May 31, 1928, discloses the 20 means whereby a plurality of the vertical cross partitions may be located across the top and securely yet adjustably held in any position in which placed.

The present invention is concerned with 30 the dividing of the long compartments across a table top, made by the vertical cross partitions, into shorter compartments by the use of short dividing partitions, preferably of glass, disposed between and at right angles to 35 adjacent cross partitions, or between the end cross partitions and the end border members attached to the top; and our invention is directed to the accomplishment of this end, as will appear from the following description 40 taken in connection with the accompanying drawing, in which,

Fig. 1 is a fragmentary perspective view illustrating a portion of a counter or a table top with an end and side border member secured thereto, a vertical cross partition, a short dividing partition and the means used to connect the dividing partition to the cross partition.

50 Fig. 2 is a fragmentary plan of the con-

struction shown in Fig. 1, showing the connection of said glass partitions.

Fig. 3 is a fragmentary elevation illustrating the application of the connecting means used to the vertical cross partitions, and

Fig. 4 is a perspective view of the connecting device used.

Like reference characters refer to like parts in the different figures of the drawing.

The counter or table top 1 is of any desired construction, usually of wood, and at the side edges thereof vertical border members 2 are secured, while at the end edges similar vertical border members 3 are connected in any desired manner. The members 2 and 3 at their inner sides and adjacent their upper edges are provided with continuous downwardly and outwardly cut grooves 4, as shown. Across the top and between the opposite side members 2 a plurality of vertical partitions 5, usually of glass, are placed and are held at their ends by connecting members 6. The specific construction of the connecting members 6 and the way the same may be adjusted lengthwise of the grooves 4 and, when the partitions 5 are used therewith, securely held against movement with respect to the members 2 on which they are mounted, is fully shown and described in the co-pending application to which reference has previously been made.

Over the upper edge of adjacent vertical partitions 5 a sheet metal connecting member of the form best shown in Fig. 4 is adapted to be placed at a plurality of points in accordance with the number of compartments into which the space between any two adjacent partitions 5, or between an end partition 5 and the end border member 3, is to be divided. Said connecting member at its upper portion has a flat vertical section 7 from which at its upper edge horizontal ledges 8 are turned at right angles. Each ledge at its inner end is provided with a downturned tongue 9, there being a slot 10 cut in the upper end of the member to divide the ledges 8 and two tongues 9 from each other. The slot 10 extends partly downward into the section 7, as shown. At each edge of the section 7 outwardly turned flanges 11 are made which

progressively increase in width as the same approach each other and which are extended downwardly and outwardly at an acute angle to the vertical to provide two downwardly extending guides 12. The guides 12 incline 5 toward each other at their lower ends and are connected at their lower ends by an integral stirrup having horizontal legs 13 connected by a cross member 14, the legs 13 also converging toward each other at their outer portions. The metal of the connecting member 10 is cut away between the legs 12 and partly into the section 7, as indicated at 15, leaving a relatively narrow portion 16 between the upper end of the opening 15 and the lower end 15 of the slot 10.

It is evident that a connecting member or a number thereof of the construction described may be placed over the upper edge of a partition 5 at any desired point, or points 20 in the length thereof, with the section 7 against one side of the partition, the ledges 8 against the upper edge and the lips 9 against the opposite side, and that said member or members may be readily moved to different positions on the partitions. When a 25 dividing partition 17, however, is applied between two of said members on adjacent partitions 5 the ends of the partitions 17 passing between the converging guides 12 spread said flanges apart and tend to bend the narrow section 16 about a vertical axis and in this manner clamp the member securely on the partition 5 on which it is placed, thereby automatically securing the dividing partition 17 in place against change of position. But 30 should it be desired to change the size of a compartment between any two adjacent partitions 5, removal of the dividing partitions 17 at once frees the connecting members used therewith for ready movement to different positions on said partition 5.

It is evident that the connecting member described may be used between any end partition 5 to hold one end of a dividing partition 45 17, the opposite end thereof extending toward the end border member 3. Said opposite end will be held in a fixture like that indicated at 6 where the same abuts against the inner side 50 of the border member 3. The construction described is economical to manufacture and is very practical and effective in use. Variations in the detail of structure can be resorted to without departing from the invention defined in the appended claims and we 55 consider our invention to cover all forms of structure coming within the scope of said claims.

We claim:

50 1. In combination, a vertical partition, a sheet metal member having a vertical section, ledges turned at right angles from the edge of said vertical section, lips turned from the free edges of said ledges, said ledges and lips respectively being separated by a slot, spaced

apart flanges extending from said vertical section, there being an opening between said flanges extending into said vertical section to a point a short distance from said slot, said flanges converging toward each other at their free ends and also converging toward each other at their outer edges, and a second vertical partition having an end received between said flanges. 70

2. A construction containing the elements 75 in combination defined in claim 1, the free ends of said flanges being connected by a stirrup comprising legs extending horizontally from the lower ends of said flanges and a cross member connecting said legs. 80

3. In combination, a vertical partition, a sheet metal member bent to form a hook adapted to extend over an edge of the partition and having spaced apart guide flanges, and a second vertical partition located at 85 right angles to the first partition with its end received between said flanges, said flanges normally converging toward each other at their outer edges whereby when the second partition is located between them the sheet 90 metal member is automatically clamped to the first partition, said flanges being of less height as they approach the upper edge of the partition and ending in a plane even with the upper edge of the vertical partition. 95

4. In combination, a vertical partition, a partition holder comprising, a vertical section adjacent said partition, hook members at an end of said section hooked over an edge of the partition, said hook members being 100 separated by a slot, and spaced apart guide flanges projecting convergently from said vertical section.

5. A construction containing the elements 105 in combination defined in claim 4, combined with an integral stirrup connecting the ends of said guide flanges and comprising a horizontal leg extending from the inner edge of each flange and a cross member connecting said legs. 110

6. In combination, a vertical partition, a second partition located at right angles to the first partition and having an end in substantially abutting engagement with the side of the first partition, and a connecting member 115 engaged with an edge of the first partition and normally freely adjustable to different lengthwise positions thereon and having means for guiding and holding said abutting end of the second partition, said guiding and holding means normally being located closer together than the thickness of the second partition, whereby it is spread apart when the second partition is placed therein thereby automatically clamping said connecting member onto said first partition. 120

In testimony whereof we affix our signatures.

EDMUND MORRIS.

ANTHONY VANDERVELD.
